UNITED STATES PATENT OFFICE.

CHARLES E. WILLIAMS, OF COLUMBUS, OHIO, ASSIGNOR TO THE LILLEY COMPANY,
OF COLUMBUS, OHIO, A CORPORATION OF OHIO.

LODGE OR FRATERNAL PARAPHERNALIA.

Application filed January 13, 1926. Serial No. 80,927.

This invention relates to improvements in lodge or fraternal paraphernalia and is especially directed to an emblem in the form of an apron, adapted to be worn by a lodge member, and provided with improved means for identifying the member and disclosing his fraternal history and affiliations.

The invention has for its principal object a lodge apron formed to comprise a main body section, a forwardly disposed foldable flap section, and indicia bearing slip, the latter being inserted between the flap and body sections and normally concealed by the flap section when the latter is worn in its lowered position, but capable of being viewed and read when the flap section is raised.

Another object rests in forming the garment so that the sections will be united along the upper edge of the garment so as to facilitate the positioning and securing of the identifying slip between the body and flap sections of the garment and to enable the identifying slip to be readily viewed and read when desired.

For a further understanding of the invention reference is to be had to the following description and the accompanying drawing, wherein:

Figure 1 is a front elevation of the improved lodge apron comprising the present invention,

Figure 2 is a vertical sectional view on the line 2-2 of Figure 1,

Figure 3 is a front elevation of the apron, showing the flap section raised to reveal the identifying slip.

Referring to the drawings the lodge apron is designated in its entirety by the numeral 1. This apron may be formed from any desired material so as to possess the desired flexibility combined with long life and wearing properties, a soft grade of leather being admirably adapted for this purpose. The apron includes a main body section 2, preferably of substantially square formation, and with this body section there is associated, to the front thereof, a foldable flap section 3 of appreciably less area than the body section. The flap section is provided, in this instance, with angu-

larly extending downwardly converging lower edges 4, while the upper edge of the flap section mates evenly with the corresponding edge of the body section. Arranged between the sections 2 and 3, and adapted to be concealed normally by the flap section is an identifying slip 5, usually formed from linen or other similar material, and the upper edge of the slip 5 terminates evenly with the corresponding edges of the sections 2 and 3.

To secure these parts together use is made of a tape 6, folded over, as shown in Figure 2, the upper edges of said sections and the entire assembly secured together by the longitudinally extending stitching 7 so as to strongly and securely unite the several parts of the apron in firmly bound relationship. The ends of the tape are extended so as to permit of the application thereof to the waist of the wearer so as to tie and hold the apron in an applied position.

Hitherto in an apron of this kind it has been customary to provide the back surface 8 of the flap section with printed indicia indicating the name of the lodge member to whom the apron belongs and his general lodge history. Due to this fact considerable difficulty has been encountered in reading this indicia, particularly when the apron is being worn, since when the flap is raised to expose the indicia the latter appears in inverted order which renders the same very difficult to view and read. In the present invention this is overcome by the employment of the separate identifying slip 5, which, as shown in Figure 3, is so disposed that when the flap is raised, the indicia may be clearly discerned and read without difficulty.

What is claimed is:

A lodge apron comprising a main body section, a flap section and an indicia bearing slip interposed between said body and flap sections, and a securing tape uniting said body and flap section and said slip along their adjoining upper edges only, said tape having its ends extending so as to permit of the application thereof to the waist of the wearer.

In testimony whereof I affix my signature.
CHARLES E. WILLIAMS.
